CLAIM

The ornamental design for universal keyboard mount, as shown and described.

DESCRIPTION

FIG. 1 is a photographic front view in perspective, looking downwardly, of a universal keyboard mount embodying our design, with the top mounting plate shown in its fully extended position;

FIG. 2 is a photographic front view, in perspective looking downwardly, of the universal keyboard mount of FIG. 1, with the top mounting plate in its "closed" position so that the curved front portion thereof is positioned with the closest spacing between it and the two rear bumpers and rear cushion;

FIG. 3 is a photographic side view, in perspective looking downwardly, of the universal keyboard mount of FIG. 1, with the top mounting plate shown in its fully extended position;

FIG. 4 is a photographic rear view, in perspective looking downwardly, of the universal keyboard mount of FIG. 1;

FIG. 5 is a photographic bottom view, in perspective looking upwardly from the right-hand side, of the universal keyboard mount of FIG. 1;

FIG. 6 is a photographic bottom view, in perspective looking upwardly from the left-hand side, of the universal keyboard mount shown in FIG. 1.

The design is characterized by the rear cushion and left-hand and right-hand bumpers, together with the top and bottom mounting plates which slide relative to each other.

The broken lines of FIGS. 3-6 are shown for illustrative purposes only.
